(57) **CLAIM**

We claim the ornamental design for an interior door release for a vehicle, as shown and described.

DESCRIPTION

FIG. 1 is a top, right perspective view of an interior door release for a vehicle, showing our new design;

FIG. 2 is a top, left perspective view thereof;

FIG. 3 is a top plan view thereof;

FIG. 4 is a right side view thereof;

FIG. 5 is a front view thereof; and,

FIG. 6 is a top plan view thereof.

The broken lines depict portions of the interior door release for the vehicle that form no part of the claimed design.
